UNITED STATES PATENT OFFICE.

PETER J. A. SCHNOOR, OF HOLSTEIN, IOWA.

NON-REFILLABLE BOTTLE.

1,137,537.

Specification of Letters Patent. Patented Apr. 27, 1915.

Application filed August 19, 1914. Serial No. 857,553.

To all whom it may concern:

Be it known that I, PETER J. A. SCHNOOR, a citizen of the United States, residing at Holstein, in the county of Ida and State of Iowa, have invented certain new and useful Improvements in Non-Refillable Bottles, of which the following is a specification, reference being had to the accompanying drawings.

10 This invention comprehends certain new and useful improvements in shipping and storing vessels and relates more particularly to bottles of the non-refillable type.

The invention has for its primary object 15 a simple and efficient construction of device of this character, the parts of which will be few in number and capable of being easily manufactured and assembled and so arranged that after they have once been assembled and the bottle filled, the contents 20 thereof may be easily poured therefrom, but difficulty will be experienced in refilling the bottle.

A further object of the invention is a 25 device of this character in which is provided a gravity actuated valve which is initially connected to a rod in such a manner that the valve may be held off of its seat for the purpose of filling the bottle, the connection 30 between the rod and the stem being such that it can be very easily disrupted so that subsequently there will be no means provided for the purpose of refilling the bottle. And the invention also aims to generally im- 35 prove devices of this character so as to render them more useful and commercially desirable.

With the above and other objects in view, as will more fully appear as the description 40 proceeds, the invention consists in certain constructions, arrangements and combination of the parts that I shall hereinafter fully describe and claim.

For a full understanding of the invention, reference is to be had to the following description and accompanying drawing, in which,

Figure 1 is a longitudinal section of a 50 bottle embodying the improvements of my invention; Fig. 2 is a horizontal sectional view on the line 2—2 of Fig. 1; and Fig. 3 is a similar view on the line 3—3 of Fig. 1.

Corresponding and like parts are referred 55 to in the following description and designated in all of the views of the accompanying drawing by like reference characters.

Referring to the drawing, the numeral 1 designates the body portion of a bottle constructed in accordance with my invention, such body portion being of any desired 60 shape, size or form, except as hereinafter noted, and 2 designates the bottle neck, the same being provided at any desired point on its interior with an annular valve seat 3.

4 designates the vale. It is provided at 65 its upper edge with an outstanding annular flange 5 adapted to rest on the seat 3 to close the outlet passage from the neck when the bottle is in its upright position, the valve being moved by gravity into both 70 open and closed positions and it being, of course, understood that just as soon as the bottle is sufficiently tilted, the valve 4 will move off of its seat and allow the contents of the bottle to pour out. When the bottle 75 is again moved to an upright position, the valve will close, as is manifest, and any attempts to pour liquid into the bottle will be frustrated. The valve 4 is provided with a 80 rod-like stem 6 which is mounted and moved through a central opening in a plate or partition 7 which is preferably cast integral with the neck above the valve seat 3 and which is provided, in addition to the opening 85 for the passage of the stem 6, with any desired number of additional openings 7', for the passage of the fluid to and out of the mouth of the bottle. Preferably, the top of the bottle is permanently closed as indicated at 8, and is provided with any desired number 90 of laterally disposed orifices 9 through which the contents of the bottle may be poured out.

It is to be particularly noted that the 95 valve stem 6 is provided at one end with a head 10 which, in the present instance is of ball-like formation and designed to rest upon the upper surface of the partition 7 when the valve 4 is upon the seat 3. Detachably connected to the stem 6 is a valve 100 raising device which, in the present instance, is in the form of a rod 11 provided at one end with spring arms 12 which are designed to engage the head 10, as clearly illustrated in the drawing. The rod 11 passes up 105 through the top 8 of the bottle and is provided at its upper end with a finger loop 13 or the like, whereby the rod may be easily grasped from the exterior of the bottle so as to raise the valve from its seat and permit the bottle to be filled initially with the desired contents. After the bottle has thus

been filled, a further pull upon the rod 11 will disrupt its connection with the stem 6 as the spring arms 12 will release the head 10 and manifestly no means are provided for 5 raising the valve off of its seat, so that while the contents of the bottle may be poured out, the valve will tend to prevent any liquid from being poured therein.

It is to be noted that the valve seat of the 10 valve 4 is relatively long and tapering and that the valve 4 is relatively long and has, generally speaking, the form of a stopper, and that the length of the valve 4 is greater than the distance between the upper end of the 15 valve seat and the partition 7, hence the lower end of the valve never entirely leaves the seat but is guided back into place in the seat. It is also to be noted that the perforations 4' in the valve are smaller in diameter than the openings 9, thus if the bottle is turned upon its side and any attempt be made to fill it, the pressure of the liquid upon the exterior face of the valve will act to close the valve and force it inward because of the relatively small perforations 4' and the relatively contracted area between the valve and the valve seat and further because of the fact that the valve will never leave its seat entirely.

30 Preferably, there is embedded in the bottom of the bottle, a plate 14 of steel or the like, whereby any attempt to blow or drill a small opening in the bottom of the bottle so as to fill the same and then seal the bottle up again, will be effectually frustrated, for the plate 14 which is embedded in the bottom of the bottle, extends from one side wall to the other and consequently, any attempt to force an opening into the bottle at this point would merely mean the entire breakage of the bottle and of course, the attempt would be frustrated.

From the foregoing description in connection with the accompanying drawing, the 45 operation of my improved bottle will be apparent. In the practical use of the device, after the parts have been assembled with the rod 11 movably and detachably connected to the valve stem 6, the rod will be moved 50 outwardly through the top of the bottle a distance sufficient to open the valve, to avoid disrupting the connection between the rod and the stem, and while the valve is thus held in its open position, the bottle may be 55 easily filled. After the bottle has been filled, a further pull upon the rod 11 will cause it to become disconnected from the valve stem, owing to the fact that the distance between the partition 7 and the top 8 is greater than 60 the distance between the partition and the top of the valve with the latter in its closed position so that when the top of the valve abuts against the lower side of the partition, the rod will not have reached the outward limit of its movement and a final pull 65

thereupon will disconnect the valve stem and rod.

It is to be understood that the rod 11, after it has been disconnected from the head 10 of the valve stem 6, is withdrawn entirely out through and from the top 8 of the bottle, the spring fingers 12 admitting of this, and subsequently the valve will have no means connected thereto whereby it may be raised from its seat for the purpose of 75 refilling the bottle.

Preferably the valve 4 is formed with any desired number of outlet passages 4' which extend obliquely therethrough, as clearly indicated in Fig. 1 and which are designed to 80 permit the ready outlet of the liquid just as soon as the valve moves away from its seat.

While the accompanying drawing illustrates what I believe to be the preferred embodiment of my invention, it is to be understood that the invention is not limited thereto, but that various changes may be made in the construction, arrangement and proportions of the parts without departing from the scope of the invention as defined 90 in the appended claims.

What is claimed, is:

1. A bottle of the character described provided in its neck with a relatively long tapering valve seat and with a partition extending across the neck between the valve seat and the mouth of the bottle, said partition being formed with outlet openings and with a centrally disposed opening, a relatively long tapering valve disposed normally on the valve seat and having a stem extending through and movable in the centrally disposed opening of the partition and provided at its upper end with a head, said valve having a length greater than the distance between the partition and the adjacent end of the valve seat, the mouth of the bottle being closed by a permanent top and being provided with lateral openings below the top, and a valve raising rod movable through the permanent top of the bottle and having detachable engagement with the head on the end of the stem.

2. A bottle of the character described provided in its neck with a relatively long tapering valve seat, and with a partition extending across the neck between the valve seat and the mouth of the bottle, the mouth of the bottle being formed with lateral discharge openings and with a permanent top, a valve normally resting upon the valve seat and having openings extending from its periphery to the upper end of the valve and having a stem passing through said partition and formed with a head, said valve being longer than the distance between the partition and the adjacent end of the valve seat, and a valve raising member movable through the top of the bottle and detachably engaging said head, the openings at the

mouth of the bottle being larger in diameter than the openings through the valve.

3. A bottle of the character described provided in its neck with a relatively long 5 tapering valve seat and with a partition between the mouth of the bottle and the valve seat, the mouth of the bottle being provided with a permanent top and with lateral discharge openings, the distance between the 10 upper face of the partition and said top being greater than the distance between the lower face of the partition and the top of the valve when the latter is in its closed position whereby to permit the disengagement 15 of a lifting rod from said head when the

valve strikes the face of the partition, the valve being greater in length than the distance between the partition and the adjacent face of the valve seat whereby to prevent the valve from entirely disengaging 20 from its seat when lifted, said valve being provided with a plurality of relatively small openings from the periphery of the valve to its upper face.

In testimony whereof I hereunto affix my 25 signature in the presence of two witnesses.

PETER J. A. SCHNOOR.
